2 SHEETS—SHEET 2.

UNITED STATES PATENT OFFICE.

ISIDOR D. BRAUNE, OF BROOKLYN, NEW YORK.

WINDOW-GUARD.

1,333,896.

Specification of Letters Patent. Patented Mar. 16, 1920.

Application filed September 21, 1917. Serial No. 192,444.

To all whom it may concern:

Be it known that I, ISIDOR D. BRAUNE, a citizen of the United States, and resident of Brooklyn, in the county of Queens and State of New York, have invented certain new and useful Improvements in Window-Guards, of which the following is a specification.

This invention relates to window guards or safety devices for windows and is directed particularly to a combination window guard and scaffolding or fire escape adapted to be attached to any common form of windows of dwellings.

One object of my invention is to provide a collapsible window guard which may be easily manipulated to position it so as to bar a window to prevent accidents.

Another object of my invention is to provide a safety device of the character described, which may also be adjusted so as to extend outwardly away from the window and serve as a scaffolding, whereby one may safely stand on the sill outside of the window as when it becomes necessary to clean the latter, or as may be expedient in case of fire, when my newly improved window guard may serve as a fire escape.

A further object of my invention is to provide a window guard which shall positively bar a window when desired, and which cannot be made ineffective by a child's tinkering therewith.

A still further object of my invention is to provide an improved window guard, which shall have the various advantages described above and effectively and efficiently accomplish the foregoing objects, and yet be neat and ornamental in construction, simple to manipulate and comparatively inexpensive to manufacture.

Other objects of my invention will appear from the detailed description, and the features of novelty will be particularly pointed out in the claims.

In the drawings accompanying this specification and forming a part thereof,

Figure 1 is a front elevational view of the outside of a window having an embodiment of my invention attached thereto;

Fig. 2 is a side elevation corresponding to Fig. 1;

Fig. 3 is a section cut along line 3—3 of Fig. 1;

Fig. 4 is a partly broken away view similar to Fig. 3 showing the guard in another

position extended outwardly away from the window and adapted to serve as a scaffolding or protection to one standing outside on the sill;

Fig. 5 is a broken away plan view partly in section corresponding to Fig. 4;

Fig. 6 is a detailed view of the means for holding the bars in a given adjusted position as to the height to which the guard is extended, and

Fig. 7 is a detailed view showing the means for positively keeping the guard in extended position.

Referring in detail to the drawing, 10 is the ordinary window comprising the upper and lower sashes 11 and 12 slidable in the usual frame 13. My improved window guard may be attached in any suitable manner to the window as for example by means of bolts 14 passing through the frame and extending into the space therein provided for the window pulley and weight.

As will be clear from the drawing the embodiment of my invention there shown consists of a series of horizontal bars 15 slidable on the normally inclined supporting members 16. These bars 15 in the form shown in the drawing are provided preferably at their ends with the small strips 17 extending in front of the bars and offset therefrom by fastening means such as the rivets or bolts 18. The horizontal bars extend behind the supporting members and the pieces 17 together with the fastening means 18 thus form guides for the horizontal bars whereby they may easily slide on the members 16. The latter are formed preferably with notches 19, and one of the horizontal bars is provided with the holding means 20 comprising preferably a member 21 formed with a wing 22 whereby it is pivoted at 23 to the bar 15 adjacent the ends thereof.

It will be seen that the piece 21 has a holding portion 24 adapted to rest in the notch and a longer, heavier portion 25 adapted by its weight to keep the holding means in position, and formed with the bent end 26 which may be easily manipulated to be raised up toward the bar so as to move the portion 24 out from the notches when a readjustment of the guard is to be made, or when it is desired to allow it to collapse.

When the window guard is to be used merely for barring a certain portion of the window the supporting members 16 are

firmly held to the frame at their upper ends by means of a hook 27 pivotally held on the frame as at 28, and normally held in engaging position by means of the spring 29. 5 The supporting members 16 are formed at the top with a curved slot 30 through which the hooks 27 enter to engage the rear wall 31 of the slot. Extending from the slotted portion and integral with the supporting members are the downturned portions 32 bent parallel to the body of the vertical members thus forming guides in which the topmost bar may slide. When it is desired to disengage the hooks 27 the topmost 10 bar is slid up between the vertical members and the downturned portions 32 until the bar lifts the hooks 27 up from engagement with the wall 31, thus releasing the inclined members from the frame. To give 15 the supporting members body and strength, they are formed at the lower end with the coiled portion 33, and to further provide for a swinging movement thereof, they are hinged at their lower end by means of the 20 hinge 34 secured to the frame, and at the upper end by means of the hinge 35 secured at one end to the downturned portion 32 and at the other to the window frame. It will 25 now be clear that the window guard may be 30 swung out by means of these hinges into the position shown in Fig. 4. In this position my improved safety device may serve as a scaffolding or fire escape and enable a person to stand with safety on the window sill 35 for the purpose, for example, of cleaning the window.

I will now describe the means whereby my device may be made to bar the window for a certain height and be positively kept in 40 position irrespective of any tinkering by children. To accomplish this purpose, I provide a hook 36 pivotally held on one side of the upper sash as at 37 and adapted in one position to engage a pin 38 held in the 45 sash. The inner vertical guide piece 39 for the window is cut away at some convenient point so as to form a notch 40, and when the upper sash is lowered until the hook 36 is disposed opposite the notched portion 40, 50 it is swung into the latter and the upper sash can not then be raised up above this position. In this position, however, the lower portion of the upper sash has forced down the link 41 of a compound lever pivoted to the frame as at 42, at the same time 55 causing the hooked link 43 to be raised into engagement with one of the horizontal bars 15 through the recess 43' therein. As will be clear from Fig. 7, the frame is properly recessed so that the link 41, which is now 60 in the dotted position shown at 44, does not interfere with the sliding of the sash in its vertical guides. Normally, of course, the link 41 extends into the space between the 65 vertical guide pieces 39 for the sash. Thus

when the upper sash is set so as to cause the hook 43 to extend outward, the window guard is held to the frame both by the hooks 27 as hereinbefore explained and also by the hooked link 43 which engages the topmost 70 horizontal bar. The window guard will thus be positively held in position and cannot possibly be manipulated by a child so as to release it from the frame and cause it to collapse. 75

In the embodiment of my invention shown in the drawings, I have provided the topmost horizontal bar with the holding means 20 adapted to coöperate with the notches in the vertical members. As to the 80 other horizontal bars, each may be suspended from the one above it by flexible means such as to chains 44 and 45 suitably secured.

It will also be clear that when hook 36 is 85 in the notch 40, the upper sash has been lowered just a little and can now be neither raised nor lowered without first manually swinging the hook out from the notch. With the barring means fully extended 90 across the window, as in Figs. 2 and 3 and the upper sash so positioned, my invention forms a very effective protection against burglars.

To give a decorative effect and also make 95 it possible to safely use the sill for placing things thereon, I provide the cagelike vertical guard portion 46 held to the sill 47 in any suitable manner, as by bars 48. Of course, this cagelike portion coöperates with 100 the barring means to provide in the position shown in Fig. 4 a scaffolding or a fire escape.

It will thus be clear that I have provided 105 an improved, collapsible and adjustable window guard, neat in appearance, simple in construction, easily manipulated, and adapted also to be positioned so as to serve as a fire escape.

Having thus described my invention what I claim is new and desire to secure by Letters Patent is—

1. A combination fire escape and window guard, comprising a stationary guard portion and adjustable guard portion comprising in combination with a window frame 115 normally inclined supporting members hinged at one end to the frame, adjustable barring means slidable on said supporting members, and adapted to be held thereto in adjusted position, means for releasably holding said supporting members at the other end thereof to the frame, and means whereby said supporting members together with the barring means may be swung out from the frame into rigid substantially vertical 125 position in alignment with said stationary guard portion.

2. A combination fire escape and window guard comprising a stationary guard portion and adjustable guard portion in combi- 130

- nation with a window frame comprising normally inclined supporting members hinged at one end to the frame, a plurality of horizontal bars, slideable on said supporting members, and adapted to be held thereto in adjusted position, means for releasably holding said supporting members at the other end thereof to the frame, and means whereby said supporting members together with the barring means may be swung out from the frame into rigid substantially vertical position in alinement with said stationary guard portion.
3. A combination fire escape and window guard comprising a stationary guard portion and adjustable guard portion in combination with a window frame comprising normally inclined supporting members hinged at one end to the frame, a plurality of horizontal bars slideable on said supporting members, and adapted to be held thereto in adjusted position, means for maintaining the bars in spaced position relative to each other, means for releasably holding said supporting members at the other end thereof to the frame, and means whereby said supporting members together with the barring means may be swung out from the frame into rigid substantially vertical position in alinement with said stationary guard portion.
4. A combination fire escape and window guard comprising a stationary guard portion and adjustable guard portion in combination with a window frame comprising normally inclined supporting members hinged at one end to the frame, barring means slideable on said supporting members and adapted to be held therein in adjusted position, means for adjusting said barring means to the height of window to be barred, means for releasably holding said supporting members at the other end thereof to the frame, and means whereby said supporting members together with the barring means may be swung out from the frame into rigid substantially vertical position in alinement with said stationary guard portion.
5. A combination fire escape or window guard comprising a stationary guard portion, and adjustable guard portion, supporting members hinged at the lower ends thereof to the window frame, barring means slideable on said supporting members, and means permitting said supports and the barring means to be swung outward from the window into a vertical position to provide together with said stationary guard a scaffolding or fire escape.
6. A combination fire escape and window guard comprising a stationary guard portion and adjustable guard portion in combination with a window frame comprising normally inclined supporting members hinged at one end to the frame, a plurality of horizontal bars slideable on said supporting members, and adapted to be held thereto in adjusted position, means pivoted on said bars for releasably holding the latter to said supporting members, and means whereby said supporting members together with the barring means may be swung out from the frame into rigid substantially vertical position in alinement with said stationary guard portion.
7. A combination fire escape and window guard comprising a stationary guard portion and adjustable guard portion in combination with a window frame comprising normally inclined supporting members hinged at one end to the frame, a plurality of horizontal bars slideable on said supporting members and adapted to be held thereto in adjusted position, gravity operated means for releasably holding said supporting members at the other end thereof to the frame, and means whereby said supporting members together with the barring means may be swung out from the frame into rigid substantially vertical position in alinement with said stationary guard portion.
